CLAIM

The ornamental design for a display screen or portion
thereof with animated graphical user interface, as shown and
described.

DESCRIPTION

The patent or application file contains at least one drawing
executed in color. Copies of this patent or patent application
publication with color drawing(s) will be provided by the
Office upon request and payment of the necessary fee.

FIG. 1 is a front view of a display screen or portion thereof
with animated graphical user interface showing a first image
of the claimed design;

FIG. 2 is a second image thereof;

FIG. 3 is a front view of a display screen or portion thereof
with animated graphical user interface showing a first image
of another embodiment thereof; and,

FIG. 4 is a second image thereof.

The broken lines in the figures show a display screen or
portion thereof, and form no part of the claimed design.

The appearance of the animated image sequentially
transitions between the images shown in FIGS. 1-2 and 3-4,
respectively. The process or period in which one image
transitions to another forms no part of the claimed design.
